W. E. MILD

ROTARY COMPRESSOR

Filed Jan. 2, 1926

INVENTOR,
William E. Mild,
Howard A. Smith,
His ATTORNEY

UNITED STATES PATENT OFFICE.

WILLIAM E. MILD, OF MOUNT VERNON, OHIO.

ROTARY COMPRESSOR.

Application filed January 2, 1926. Serial No. 78,821.

This invention relates to new and useful improvements in rotary compressors.

It is the principal object of my invention to provide a rotary compressor of the single or multi-stage type in which the rotor blades are forced outwardly against the walls of the cylinder by the pressure of the oil which lubricates them. To achieve this result the rotor shaft is hollow to receive the oil from a cooler which is in communication with an oil separator that is connected with the discharge part of the compressor. Through this hollow shaft the oil flows to port openings in the rotor under the blades to force them against the cylinder walls.

In those instances where the blades are held against the walls of the cylinder by springs, an excess of power over that required in my device is necessary to turn the rotor in view of the friction caused by the spring tension. Centrifugal force is not satisfactory as a means of drawing the blades outwardly, since the pressure at the compression point forces the blades back in the slotted rotor and therefore lessens the work accomplished. My invention obviates these difficulties in, and increases the efficiency of, a rotary compressor.

Other important and incidental objects will be brought out in the following specification and particularly set forth in the subjoined claim.

In the accompanying drawings, Figure 1 is a longitudinal sectional view taken through my rotary compressor. And Figure 2 is a cross sectional view thereof taken on the line 2-2 of Figure 1.

Referring to the accompanying drawings for a detailed description of my invention, the numeral 1 designates a cylindrical rotor casing that is surrounded by an exterior casing 2 which provides around it a space 3 to receive a cooling medium such as water. Journaled in the casing 1 is a shaft 4 formed with a hollow center 5 that extends from one end of it well into that portion of the same which lies within the casing 1. The other end of the shaft 4 projects well beyond the casing 1 for connection to a prime mover such as an electric motor 5a. The shaft 4 is eccentric with respect to the casing 1, and mounted upon it within the casing is a rotor hub 6 that is formed with radial cavities 7 to receive blades 8. At their inner ends these cavities communicate through ports 9 in the rotor hub and registering ports 10 in

the shaft 4, with the hollow center 5 of the latter. The blades 8 are forced against the inner wall of the casing 1 by a lubricating fluid such as oil which is admitted below them in the cavities 7 through the ports 10 and 9 and the hollow portion of the shaft 4 from means soon to be described.

Air or other gas for compression in a well known manner by the rotating blades 8 within the casing 1, is admitted to the latter through an inlet port, 11 and tube 12, and is discharged with the lubricating oil through an outlet port 13. Communicating with the latter is tubing 14 by which the compressed air and the oil is admitted to an oil separator 15. Within the upper portion of the latter is a baffle 16 around which the air passes into an outlet pipe 17, while the oil drops down into a coil 18 which is cooled by water 75 or other cooling means admitted to the cooling portion of the separator 15 through a pipe line 19. The latter communicates with the cooling space 3 within the casing 1, so that after the water which has been admitted thereto by a pipe 20 has cooled the rotor mechanism, it may be employed to cool the oil in the coil 18.

The cooled oil passes from the bottom of the coil 18 into a vertical oil pipe 21 which, 85 by a valve casing 22, is connected to a horizontal pipe 23 that is secured to a T coupling 24. From one open end of the latter oil flows through a pipe line 25 to the upper portion of the casing 1, where it is received 90 by a horizontal passage 26 in the top of the latter and from which it descends through vertical side passages 27, 27 to the bearings within the casing.

Connected to the remaining open end of 95 the T coupling 24 is a tube 28 which, through a right angled bend 29, communicates with the hollow center 5 of the shaft 4 to deliver oil thereto. This oil will in turn pass through the ports 10 in the shaft, and the 100 registering ports 9 in the rotor, into the cavities 7 in the latter to force the blades 8 therein outwardly into engagement with the wall of the casing. Thus, instead of springs and the action of centrifugal force, objectionable for the reasons hereinbefore stated, I employ the rotor mechanism lubricant for the purpose of maintaining its blades in firm engagement with the cylinder wall. This conduces to economy and efficiency in 110 a rotary compressor.

I do not wish to be limited to the details

of construction and arrangement herein shown and described, and any changes or modifications may be made therein within the scope of the subjoined claim.

6 Having described my invention, I claim:
In a rotary gas compressor, a casing, a rotor hub in the casing formed with radial cavities and having a hollow center in communication with the latter, outwardly movable blades in said cavities to compress gas in said casing, an oil separator in communication with said casing to receive compressed gas and oil therefrom, a cooling coil in said separator for the oil separated from the gas,

an oil outlet pipe projecting downwardly 15 from said coil, a T connected to the outer end of said pipe, a pipe line leading from one end of said T to the interior of the casing and a second pipe line leading from the remaining end of said T to the hollow center 20 of the rotor hub to pass oil therethrough to the blade cavities to force said blades outwardly against the interior surface of the casing wall, for the purpose specified.

In witness whereof I have hereunto set my 25 hand this 31 day of December, 1925.

WILLIAM E. MILD.
